UNITED STATES PATENT OFFICE.

AUGUST ZIDOVEC, OF SAN RAFAEL, CALIFORNIA.

CAN OPENER.

Application filed December 19, 1922. Serial No. 607,859.

To all whom it may concern:

Be it known that I, AUGUST ZIDOVEC, a citizen of the United States, residing at San Rafael, in the county of Marin and State 5 of California, have invented new and useful Improvements in Can Openers, of which the following is a specification.

This invention relates to improvements in cap openers and the primary object is to 10 provide a can opener which will be simple as to construction, compact, strong, durable and capable of being easily operated to evenly cut the top of a can or like receptacle.

One of the objects of the invention is to 15 provide a novel mounting for the knife, which mounting provides for attaching the knife to handles of the plier type whereby upon moving the handles together an easy 20 and effective cutting action will be provided by the knife.

The invention further consists of the particular combination, inter-relation and association of elements thereof for the purpose 25 of generally improving and simplifying the construction and operation of can opening devices of the type described.

The invention possesses other advantages and features some of which, with the fore- 30 going will be set forth at length in the following description where I shall outline in full that form of the invention which I have selected for illustration in the drawings accompanying and forming a part of the 35 present specification. In said drawings I have shown one form of the construction of my invention, but it is to be understood that I do not limit myself to such form since the invention as expressed in the claims may be 40 embodied in a plurality of forms.

Referring to the drawings:

Fig. 1 represents a top plan view of the 45 opener of my invention as when in position of use, it being shown as applied to a can with the handles spread apart.

Fig. 2 represents a bottom plan view of the 50 opener, the handles being locked together.

Fig. 3 represents a side elevation of the 55 opener.

Fig. 4 represents a cross sectional view 60 taken on line 4—4 of Fig. 1; Fig. 5 is a top plan view of a modified form of link; Fig. 6 is a side elevation of the link shown in 65 Fig. 5.

Referring to the embodiment of the in-

vention shown in the accompanying drawings, 1 and 2 designate handles which are pivoted intermediate of their ends as at 3, and which cross one another where pivoted. 60 The pivot 3 is provided by forming complementary annular grooves 4 in the material of the handles where the latter are crossed. A suitable pivot member 5 joins the handles where portions thereof contact with one another centrally of the grooves 4. A spring 6 is mounted in the space provided by the registering grooves 4 and its ends are anchored in off-set extensions 7 of the respective grooves. This spring tends to force the 70 handles apart at all times and thereby assists in the operation of the opener. To limit the movement of the handles, there is provided a projection 8 on one handle engaging in an arcuate groove 9 in the other 75 handle. When the projection engages one end of the groove, the handles are limited in their movement away from one another.

The handle 1 extends beyond the pivot 3 and is enlarged so as to form a substantially 80 flat plate-like portion 10. A line drawn lengthwise through the mediate portion of the plate portion would intersect the pivot 3 when the handles are in position to operate the opener. This will be apparent 85 from inspection of Fig. 1. The other handle 1 is extended in the form of a flat arm 11, the longitudinal axis of which is parallel to a longitudinal axis of the opener, through the pivot 3. The arm-like projection 11 extends considerably beyond the outer edge 90 of the plate-like portion 10 and is adapted to overlie the upper edge of a can, which latter is shown at A, in Fig. 1. The member 11 is off-set, as shown at 12, with respect to the position of the handle portion proper so as to provide for the proper disposition of the arm 11 with relation to the top of the can. On the under side of this member 11 there is provided an L-shaped 95 grip member 13 having at one end a sharp edge 13'. The sharp edge 13' is adapted to bite against the can along the outer side of the latter substantially at the outer side of the bead to facilitate the cutting operation, as will be later described. The member 13 having the shape described better withstands the strains directed thereto and serves as a reinforcing element.

The blade 2 carries a cutting knife 14 110 which has an upright cutting edge inclined to the vertical. The knife is rigidly fastened

in one end of an arcuate link 15, the other end of the link being pivoted as at 16 on the under side of the plate portion 10. The pivot member extends through the plate portion 5 at a point to one side of the central portion of the latter to the left of the pivot 3. A finger piece 17 extends outwardly from the link 15 at a point opposite from where the knife or blade is attached 10 and also acts as a stop to limit the swinging action of the link. When the link is swung outwardly the finger piece 17 engages the adjacent edge of the plate portion 10. Upon movement in the other direction, the link is limited by engagement with the handle 1. The link is of such length that when the handles are spread apart, as shown in Fig. 1, the knife will be disposed considerably to one side, to the right of the 15 pivot 3 whereby when the handles are compressed the movement of the knife is an arcuate and comparatively long one. The leverage action on the knife is made very effective, due to the construction of the link 20 and its relation to the knife and handles.

To provide for holding the handles closed as shown in Fig. 2, a portion of the handle 1 has a projection 18 which is adapted to extend into a recess or notch 19 formed in 30 the outer end of the link 15. By moving the link inward or outward on its pivot, the projection will be caused to extend into and out of the recess 19.

In use of the opener, it is placed with 35 the handles open, as shown in Fig. 1, so that the arm portion 11 will extend over the top of the can and the sharp edge 13 of the gripping member 13 will engage the outer side of the bead of the can. The link is 40 adjusted on its pivot so that the blade will be brought into proper position on the top of the can adjacent to the bead. By pressing downwardly, the knife will puncture the can and permit the members 11 and 13 45 to assume proper relation to the can. Upon compressing the handles, the member 13 will grip against the side of the can and as the handle 2 is moved towards the handle 1, the links swing and move the knife in an 50 arcuate path corresponding to the curve of the can, causing a smooth, even cut to be made. Upon releasing the handles the spring will force them apart and a fresh 55 grip is taken with the member 12. The cutting is continued in this manner until the top of the can has been entirely cut.

Referring to Figs. 5 and 6 wherein I have shown a modified form of link to be used in place of the longer arcuate link 15, the 60 modified link comprises two arcuate links 40 and 41 pivoted to one another as at 42. The link 40 at one end, has an opening 43 to provide for its pivotal connection with the portion 10 of the handle 2. The outer end 65 of the link 40 is adapted to support the cut-

ter not shown. By this double link arrangement a greater movement of the knife upon each action of the operating handles is provided and by the double link, the knife will more readily follow the curve of the can without producing a jagged edge or cut. The link 4, has a member 44 thereof for limiting the relative movement of said links.

It will be noted that the pivot 16 for the link 15 and the cutter of knife 14 are disposed on opposite sides of the pivot 5 for the handles, that is to say, they are on opposite sides of a center line drawn longitudinally of the handles through the pivot 5. This disposes the knife close to the gripper 13, applies the leverage in such manner as to prevent buckling or bending in of the side of the can. In openers of which I am aware, it has been the practice to mount the can gripping member on one extension of the handles and the knife at the outer extremity of a corresponding extension of the other handle, said extensions forming a Y-shape figure. This disposes the knife and gripper in widely separated positions and when the leverage is applied, the force against the gripper is such as it often tends to press in or buckle the side of the can. With the arrangement of my invention this is prevented.

The edge of the gripper 13 is prevented from breaking by the curved side of the member 13'.

I claim:

1. A can opener comprising handles pivoted to one another, the handles having portions which extend beyond the pivot which portions are adapted to extend over the top of a can to be cut, a gripping member on the under side of one of said portions arranged to engage the outer side of the can adjacent the upper end thereof, a link pivoted at one end to the other of said portion and extending across the first named portion and a cutting knife carried by and depending from said link.

2. A can opener comprising handles pivoted to one another intermediate of their ends and having portions of which extend beyond the pivot and are adapted to extend over the top of a can to be cut, a gripping member on the under side of one of said portions arranged to engage the outer side of the can adjacent the upper end thereof, a link pivoted at one end to the other of said portions and a cutting knife carried by and depending from said link, said link, pivot and the cutting knife being disposed on opposite sides of the handle pivot.

3. A can opener comprising handles pivoted to one another and having portions extending forwardly beyond the pivot, a gripping member on one of said portions, a link pivoted to the other portion and a knife carried by said link, said pivot for the link

and the knife being disposed on opposite sides of the pivot for the handle.

4. A can opener comprising handles pivoted to one another and having portions extending forwardly beyond said pivot, a can gripping member on one of said portions, a member pivoted on the other of said portions and a knife carried by said member, said knife and pivot for said member being disposed on opposite sides of the plane of a line drawn longitudinally of the handles and through the center of the pivot therefor.

5. A can opener comprising handles piv-

oted to one another and having portions extending beyond said pivot, a can gripping member on one of said portions, a member pivoted on the other of said portions and extending across the first named portion and a knife carried by said member and disposed so as to substantially meet said gripping member at the plane of a line drawn centrally through the handle pivot and longitudinally of the handles at the finish of a cutting stroke. 15 20

AUGUST ZIDOVEC.
